UNITED STATES PATENT OFFICE.

MATHEW LOFBACK, OF SEBEKA, MINNESOTA.

FUEL ECONOMIZER FOR INTERNAL-COMBUSTION ENGINES.

Application filed September 22, 1922. Serial No. 589,915.

To all whom it may concern:

Be it known that I, MATHEW LOFBACK, a citizen of the United States, residing at Sebeka, in the county of Wadena and State 5 of Minnesota, have invented certain new and useful Improvements in Fuel Economizers for Internal-Combustion Engines; and I do hereby declare the following to be a full, clear, and exact description of the invention, 10 such as will enable others skilled in the art to which it appertains to make and use the same.

This invention relates to an internal combustion engine and particularly to such an 15 engine of the automobile type. In such engines, there is considerable leakage of the fuel mixture or gas past the pistons in the cylinders, which gas passes into the engine or crank casing. A considerable volume of 20 combustible gas is therefore contained in the crank casing:

It is an object of this invention to provide means on the engine for utilizing this 25 gas contained in the crank or engine casing.

It is a further object of the invention to accomplish this result by providing a conduit connected to the crank casing and also connected to the fuel intake conduit of the 30 engine.

It is more specifically an object of the invention to provide such a conduit, together 35 with a screening means for preventing solid matter being drawn thereinto from the crank casing and to provide a valve in the air intake conduit beyond the connection of the conduit from the crank casing thereto.

These and other objects and advantages of the invention will more fully appear from the following description made in connection 40 with the accompanying drawings in which the single view shows a side elevation of an internal combustion engine with the invention applied thereto.

Referring to the drawing, an automobile 45 engine of the well known Ford type is more or less diagrammatically represented and which illustrates the intake manifold 1, the carbureter 2, the air intake conduit 3, the adjusting means 4 for the carbureter and the 50 engine and crank casing 5. The carbureter has the usual throttle valve arm 6 and the choke valve arm 7. In the type of engine illustrated, there is usually a pipe, such as shown at 8, connected to the crank casing 55 and having air passages thereinto to equalize the pressure in the crank casing with

that of the atmosphere, which pipe is commonly known as the breather pipe. In the embodiment of the invention illustrated, a conduit 9 is provided connected at one end 60 to the pipe 8 and thus to the crank casing and connected at its other end to the air intake conduit 3. A conduit 9 is provided with a flexible section 10 so that the same may be somewhat bent to pass around the 65 operating means 4. The pipe 8 has a cap 15 thereon of substantially semi-spherical shape about the lower edge of which the air passes into said pipe. A screen 11 is placed in the pipe 8 below the conduit 9 and a wing 70 or diaphragm valve 12 is provided in the conduit 3 above the conduit 10 having the operating handle 13 and being frictionally held in adjusted position by a spring 14.

In operation, air will be drawn through 75 the conduit 3, as usual, and through the carbureter 2 into the intake manifold 1. The gas contained in the crank casing 5 will also be drawn into the carbureter through the conduit 9, as indicated by the arrows and 80 some air will pass into the pipe 8 through the cap 15, as indicated by the arrows. The amount of suction through the conduit 9 can be varied by adjusting the valve 12 and any solid or other objectionable matter will be 85 prevented from passing into the conduit 9 by the screen 11. The combustible gases passing into the crank casing 5 will thus be utilized and will be carried with the heated air into the carbureter 2 where they will 90 be mixed with the usual fuel mixture. The air and combustible gas in the crank casing is also churned with the oil therein and becomes somewhat emulsified and the mixing 95 of this air with the fuel assists in efficiently lubricating the valves and cylinder. The amount of oil thus carried, however, is not sufficient to cause any objectionable results in the cylinder.

The applicant has demonstrated the invention in actual practice and finds that considerable more mileage can be obtained from a given quantity of fuel by the use of the invention. When the same is used the carbureter can be adjusted to feed much less 105 fuel than when the invention is not used.

While in the embodiment of the invention illustrated the conduit 9 connects the crank casing with the intake pipe 3 beyond the carbureter, it is within the scope of the 110 present invention to connect said conduit at any point in the intake pipe or manifold.

From the above description it is seen that applicant has provided a simple and efficient device for economizing fuel. The parts of the device are extremely simple and can be 5 readily and inexpensively applied to standard automobile engines with no appreciable change in the parts thereof.

It will, of course, be understood that various changes may be made in the form, 10 details and arrangement of the parts of the invention without departing from the scope of applicant's invention, which, generally stated, consists in the matter shown and described and set forth in the appended claim.

15 What is claimed is:

The combination with an internal combus-

tion engine having a crank casing, a breather pipe at one end thereof, an intake manifold, a carbureter connected at one side to said manifold, an air inlet pipe connected to the other side of said carbureter, a manually controlled throttle valve on the manifold side of the carbureter, and a manually controlled choke valve at the air inlet pipe end of the carbureter, of an unobstructed conduit extending from the breather pipe directly and substantially horizontally to said air inlet pipe, and a manually controlled adjustable valve adjacent the top of said air inlet pipe and above the end of said conduit. 20 25 30

In testimony whereof I affix my signature.
MATHEW LOFBACK.
